CIRCUIT BREAKER

John B. MacNeill, Wilkinsburg, Pa., assignor to
Westinghouse Electric Corporation, East Pitts-
burgh, Pa., a corporation of Pennsylvania

Application October 25, 1944, Serial No. 560,222

7 Claims. (Cl. 200—82)

1

This invention relates generally to circuit breakers, and more particularly to circuit breaker operating means.

Circuit breakers employed for the protection of high power circuits encounter varying resistance to operation in different parts of their cycle of operation. Thus, in a circuit opening operation, it is desired that the breaker contacts separate as fast as possible to aid in extinguishing the arc, and for this reason breaker contacts are usually arranged to be tripped open free of the greater part of the contact actuating mechanism, to thereby reduce the mass which need be moved. During a circuit closing operation of circuit breaker contacts, relatively high resistance to movement of the parts is encountered during the final portion of this movement, due to several factors among which are the magnetic forces encountered just at the time contact engagement occurs, and the necessity for establishing the necessary contact pressure in the final closed circuit position. Since the movement of the breaker contacts must be arrested suddenly at the closed circuit position, it is also desirable that the momentum of the moving parts at the end of the closing stroke be relatively small. One way of accomplishing this is to vary the motive force applied to the moving contact of the breaker so that but a relatively small force is applied during initial closing movement, and a larger force is applied when the resistance to movement increases, at the final portion of this movement. Various means have been suggested in the past for varying the force applied to the moving contacts during a circuit closing operation of a circuit breaker, but these generally involve some extraneous means, such as special linkages, throttle valves, and the like.

One object of this invention is to provide novel circuit breaker actuating means which is coordinated with the breaker contacts so as to exert a relatively small force during the first portion of circuit closing movement, and to automatically exert a greater force during the final portion of the circuit closing movement.

Another object of this invention is to provide novel circuit breaker actuating means adapted to exert a variable force on the movable breaker contact during circuit closing movement, but adapted to exert a relatively large and constant force on the moving contact during circuit opening movement thereof.

Another object of this invention is to provide novel fluid motor means for actuating circuit breaker contacts, so constructed and arranged as

2

to exert a variable force in the movement thereof in one direction.

These and other objects of this invention will become more apparent upon consideration of the following detailed description of preferred embodiments thereof, when taken in connection with the attached drawings, in which:

Fig. 1 is a side elevation view of a circuit breaker embodying this invention, with certain of the parts in section and certain other parts broken away;

Fig. 2 is a side elevation view partially in section of a modified form of circuit breaker embodying this invention; and

Fig. 3 is a longitudinal section view through a modified form of motor adapted to actuate a circuit breaker in accordance with this invention;

Referring to Fig. 1 of the drawings the circuit breaker illustrated includes current interrupting means 2, illustrated schematically as including a bridging contact 4, preferably composed of a plurality of spring leaves of any suitable resilient conducting material, and adapted to cooperate with a pair of spaced fixed contacts 6. The interrupting means 2 may be of any well known type, as the bridging contact 4 and fixed contacts 6 are shown merely for the purpose of illustrating the position of the parts of the interrupter during operation of a circuit breaker embodying this invention. Bridging contact 4 is adapted to be operated by means of a linkage, schematically illustrated at 8, which connects contact 4 with a breaker operating rod 10. As shown, bridging contact 4 is movable to open the circuit by movement away from fixed contact 6 under the influence of gravity, and preferably a relatively strong biasing spring (not shown) is also employed to bias bridging contact 4 in a direction to open the circuit.

Operating rod 10 is adapted to be connected to a closing motor 40, by mechanism preferably of the type permitting the contact operating rod to trip free of the motor on a circuit opening operation. Such mechanism may be of any desired type, and that illustrated is similar to that disclosed in J. B. MacNeill et al. Patent 2,144,502, issued January 17, 1939, and also to the mechanism shown in H. J. Lingal Patent 2,290,977, issued July 28, 1942, both patents being assigned to the assignee of this invention. This mechanism comprises in general a pair of breaker levers 12 between which operating rod 10 is received and pivotally mounted, as by a pivot pin 14, at a point substantially intermediate the ends of breaker levers 12. Closing levers 17 are

provided at each side of breaker levers 12, and are pivotally connected therewith at one end as by a pivot pin 16. Closing levers 17 are pivotally mounted at their opposite ends on pivot pins 28 mounted on the fabricated frame structure 27, and the adjacent ends of breaker levers 12 are connected by a pin having a latch roller 18 thereon, with the axis of latch roller 18 substantially coinciding with the axis of pivot pins 28. Latch roller 18 on breaker levers 12 is adapted to cooperate with a latch mechanism 20 to be normally held at the position shown in Fig. 1. At the opposite end of breaker lever 17, pivot pin 16 is also provided with a latch roller 22, and this roller is adapted to cooperate with a latch lever 24 pivotally mounted as at 26 on frame structure 27, to be held by latch lever 24 in the closed circuit position of the breaker. Latch lever 24 is biased in a clockwise direction as viewed in Fig. 1, by a latch spring 30 connected between the latch lever and frame structure 27. Breaker levers 12 are bridged at their ends adjacent pivot pin 16 by a release bar 25, for a purpose to be described. Closing levers 17 are acted upon by retrieving springs 32 (only one of which is shown) which react between the respective levers 17 and frame structure 27, to bias closing lever 17 in a counterclockwise direction about pivot pins 28, as viewed in Fig. 1 of the drawing.

Closing levers 17 of the trip-free mechanism are adapted to be connected to motor 40 by means of connecting links 36, pivotally connected to the levers as at 34, and adapted to be pivotally connected to the piston rod 38 of the motor 40.

Latch mechanism 20 comprises a latch lever 42 pivotally mounted at 43 on the frame structure, with the movement thereof being controlled by a pair of toggle levers 44 and 46. Toggle lever 44 is pivotally connected with latch lever 42 by a pivot pin 50, and toggle lever 46 is pivotally mounted on frame structure 27 by means of a pivot pin 52. The two toggle levers 44 and 46 are connected by a knee pivot 48, and are biased to the right as viewed in Fig. 1 to substantially the position shown where the toggle levers are in a straightened condition, by means of a coil tension spring 54 engaging toggle lever 46 adjacent knee pivot 48.

Toggle lever 46 is provided with a lateral extension 56 adapted to overlie the plunger rod 58 of a trip device 59 also mounted on frame structure 27. Trip device 59 includes a movable core 60 to which plunger rod 58 is attached, and the core is provided in a coil 62 which also has a stationary core part 64.

The breaker is illustrated in Fig. 1 at the position the parts occupy during a circuit closing operation, just prior to engagement of bridging contact 4 with fixed contacts 6. It will be noted that at this position of the parts closing levers 17 and breaker levers 12 move together, because breaker levers 12 are held by latch mechanism 20 to pivot about the same axis 28 as closing levers 17. Accordingly, the breaker will be finally closed by continued downward movement of motor piston rod 38 and finally cause latch roller 22 to be engaged and held by latch lever 24 at the fully closed position.

Now if an overload or other electrical condition occurs which energizes trip coil 62 sufficient-
ly to attract movable core 60 upwardly, the toggle comprising levers 44 and 46 will be broken to the left thus moving latch lever 42 to the left and releasing latch roller 18. This then permits breaker levers 12 to move in a clockwise manner

about pivot pin 16, under the influence of the contact biasing means, to open the circuit free of closing levers 17 and closing motor 40. During such clockwise movement of breaker levers 12 about pivot pin 16, latch release bar 25 will engage latch lever 24 and move it to the left thus releasing latch roller 22, and permitting retrieving springs 32 to move closing levers 17 in a counterclockwise manner relative to their pivot 28. Such counterclockwise rotation of closing levers 17 results in counterclockwise rotation of breaker levers 12 about their pivot pin 14 on contact rod 10, and this causes latch roller 18 carried by breaker levers 12 to reset beneath latch lever 42. At this point in the operation, the apparatus is conditioned for a circuit closing operation which will occur by operation of motor 40 in a manner to move piston rod 38 downwardly. During the circuit closing operation, breaker levers 12 and closing levers 17 move together, as previously explained.

In order to prevent return movement of toggle levers 44 and 46 of latch mechanism 20 to the right, when latch roller 18 is released, a latch blocking lever 98 is provided adapted to automatically hold toggle levers 44 and 46 in the collapsed position to which they are moved by trip device 59, until latch roller 18 on breaker lever 17 is in a position to engage latch lever 42. Latch blocking lever 98 is substantially L-shaped in form, being pivotally mounted on the frame structure as on pivot pin 43, and having an upper edge adapted to be engaged by latch roller 18 when it is in a position to be held by latch lever 42, and the blocking lever has the other end of spring 54 anchored thereto, so as to be biased for rotation about pivot pin 43 in a clockwise direction. Blocking lever 98 has an extension 100 adapted to lie just beneath knee pivot 48 of the toggle when latch roller 18 is engaged and held by latch lever 42, but when latch roller 18 is released and the breaker levers 12 move upwardly, blocking lever 98 may move in a clockwise direction a sufficient amount to present the end of extension 100 in a blocking position with respect to knee pivot pin 48.

During a circuit closing operation of the breaker, in moving from the full open position of the contacts to the position shown in Fig. 1, relatively little force is needed to operate bridging contact 4, because there is relatively little opposition to movement of the parts to this position. However, in moving from the position shown in Fig. 1 to the fully closed position, it is not only necessary to stress bridging contact 4 an amount sufficient to obtain the necessary contact pressure in the closed circuit position, but in closing on overloads or short circuits, high magnetic forces are also encountered during this final closing movement, and if arcing should occur prior to engagement of the contacts, additional forces will be encountered at this final part of the closing movement. It is not desirable that the force required during this final part of the circuit closing operation be exerted during the initial part of the closing operation, because this would result in a relatively great momentum of the moving parts which would have to be dissipated when the closing operation is completed. Since this would require relatively massive parts or complicated shock absorbing mechanism, it is more desirable that the force exerted during a circuit closing operation be kept low during the first part of the circuit closing operation, and be automatically increased at the final part of this oper-

ation, in order to successfully overcome the relatively large resistances encountered at this point in the operation, without resort to increased masses or shock absorbing mechanism.

In accordance with this invention, the force available during a circuit closing operation is automatically controlled by the motor 40. The closing motor 40 may be of the fluid, cylinder and piston type illustrated, with the cylinder including a large diameter portion 66 and a smaller diameter portion 68, and with the piston having a corresponding large diameter portion 70, and small diameter portion 72. The cylinder of the motor is shown as integral with frame structure 27 at its upper end, and has the lower end thereof closed by a cylinder head 74 secured thereto as by bolts 75, with a vent 76 provided in the cylinder head.

The side wall of the motor cylinder is provided with an inlet opening 78 communicating with a longitudinally extending inlet passage 80 formed in the cylinder wall having at opposite ends thereof an inlet port 82 at the upper end of small diameter portion 68 of the cylinder, and a second inlet port 84 at an intermediate point of the large diameter portion 66 of the cylinder.

Fluid under pressure may be obtained from any desired source such, for example, as a pressure tank 86, which is connected by a conduit 88 with an inlet valve 90, which, in turn, communicates with cylinder inlet 78 by means of a conduit 92. Inlet valve 90 is provided with an operating coil 96, and is shown in a position to admit fluid to motor 40, with vent 94 in the valve structure being closed.

It will be observed that when the circuit breaker is at its full open position, motor piston 70, 72 will be at the upper end of its travel in cylinder 66, 68 wherein the large diameter portion 70 of the piston closes inlet port 84, so that when fluid is admitted to the cylinder by energizing coil 96 of the inlet valve, it will be admitted to the cylinder only through inlet port 82. This means that at the start of the circuit closing operation, fluid under pressure is admitted only to move the small diameter portion 72 of the motor piston. However, when bridging contact 4 reaches the position shown in Fig. 1 where it is about to engage fixed contact 6, and where a relatively high resistance is encountered in continuing the closing operation to the fully closed position, large diameter portion 70 of the motor piston is beginning to uncover inlet port 84, and thus admit fluid under pressure to the large diameter portion 66 of the cylinder, so that the total force then available to move the piston during this final part of the circuit closing operation is automatically increased by movement of the motor piston itself, and of course this movement is correlated with the movement of bridging contact 4 of the breaker.

It will be observed that after the breaker has attained its fully closed circuit position and coil 96 of the inlet valve is deenergized, this valve may return to its original position under the influence of a biasing spring or the like (not shown), to close off fluid under pressure from conduit 92, and open this conduit to vent 94, so that fluid under pressure within the motor cylinder may escape to the atmosphere. Preferably valve 90 is biased to its lower position, and moved upwardly only when coil 96 is energized.

Fig. 2 illustrates an application of this invention to a circuit breaker utilizing gas under pressure for actuating the breaker contacts to both

open and closed positions, and for extinguishing the arc formed when the contacts separate. In this type of breaker, the contacts may be actuated in both directions by the fluid motor, and the device illustrated in Fig. 2 illustrates this type of motor and the way in which a motor constructed in accordance with this invention may be utilized for operating a breaker of this type.

The particular compressed gas breaker illustrated is provided with a gas storage tank 102 on which is supported a conduit 104 which communicates at its lower end with the storage tank. Conduit 104 is of an insulating material, and is provided at its point of communication with storage tank 102, with a valve 106 for controlling the flow of gas therethrough. An arc chute 108 is secured to the upper end of conduit 104, and is braced by a bar 110 also connected between the arc chute and storage tank. A stationary contact structure 112 is adapted to be mounted within arc chute 108.

The moving contact structure of this circuit breaker comprises a substantially L-shaped contact lever 114 pivotally mounted at 116 on a bracket 117 secured to bar 110 and conduit 104. The outer end of bracket 117 carries a bumper 118 for limiting opening movement of contact lever 114. The contact lever is adapted to be actuated by a connecting rod 120 of insulating material, which is pivotally connected with an intermediate portion of the contact lever as at 122, and pivotally connected at its other end to a cam plate 124. The cam plate 124 is mounted on a drive shaft 126 suitably mounted in bearings provided on storage tank 102, and the drive shaft is provided with an actuating crank 128 connected by means of links 130 to the piston rod 132 of a compressed gas motor 134. Cam plate 124 is adapted to cooperate with a cam roller 136 provided on one arm of a bell crank 138, with the other arm thereof connected with the stem of valve 106. A compression spring 140 is provided for urging the valve stem in a direction to cause cam roller 136 to engage cam plate 124 and to close valve 106.

The circuit breaker illustrated in Fig. 2 is, like that shown in Fig. 1, shown with the parts at the position they occupy just prior to engagement of the contacts. Accordingly, to move contact lever 114 into engagement with fixed contact 112, it is necessary that motor piston rod 132 be moved further upwardly, and it will be observed that such movement causes cam roller 136 to be received in a notch 125 provided at one end of cam plate 124. When the circuit breaker is actuated to open the circuit, piston rod 132 is moved downwardly causing counterclockwise rotation of shaft 126 and cam plate 124. Initial movement of the cam plate causes bell crank 138 to be rotated in a clockwise manner to open blast valve 106 and cause a blast of compressed gas from the storage tank through conduit 104, to be directed through the space between the contacts when they separate. Such movement of cam plate 124 also causes opening of the contacts by means of connecting rod 120.

Since substantially the same high forces are encountered with this breaker during the final part of the circuit closing operation as set forth previously in connection with the breaker illustrated in Fig. 1, it is also desirable that the closing force be relatively small at the start of the closing operation, and that it be automatically increased during such final part thereof. Accordingly, in accordance with this invention, a fluid

motor is provided having a cylinder with a portion 142 of relatively large diameter, and a portion 144 relatively small in diameter. The cylinder has the outer end of the large diameter portion closed by a cylinder head 146, and the lower end of the small diameter portion is seated on a supporting plate 148 which also acts as a cylinder head. The motor piston has a corresponding large diameter portion 150 and small diameter portion 152. A supply conduit 154 is provided from storage tank 102, with electromagnetically operated valves 156 and 158, respectively, controlling the admission of gas to opposite ends of the motor cylinder. Thus, valve 156 controls the admission of gas from supply conduit 154 to a pipe 160 leading to an inlet port at the upper end of the large diameter portion 142 of the cylinder, and valve 158 controls the admission of fluid from supply conduit 154 to a longitudinally extending inlet passage 162 formed in the side wall of the motor cylinder. This inlet passage 162 is provided with a bottom inlet port 164 at the lower end of small diameter portion 144 of the cylinder, and with an intermediate inlet port 166 located intermediate the ends of the large diameter portion 142 of the cylinder. Valves 156 and 158 may be of any desired type, preferably of a type adapted to admit fluid under pressure to the motor cylinder in one position, and in another position to vent the cylinder to atmosphere, like the valve 90 shown in Fig. 1.

In the operation of the motor structure shown in Fig. 2, during a circuit closing operation starting from the point where the motor piston is at its lowermost position, and the breaker contact lever is at its open position wherein it is in engagement with bumper 118, it will be observed that operation of valve 158 to admit fluid to inlet passage 162 results in fluid being admitted to the cylinder solely through port 164, because port 166 will be closed by the large diameter portion 150 of the motor piston. This results in a relatively small force applied to the motor piston during the first part of the circuit closing operation, until the motor and contact lever 114 reach the position shown in Fig. 2, just prior to engagement of contact lever 114 with fixed contact structure 112. At this point the large diameter portion 150 of the motor piston starts to uncover port 166, thus admitting fluid pressure to the large diameter portion 142 of the cylinder, thereby increasing the force exerted by the motor on contact lever 114 during this final portion of the circuit closing operation.

When it is desired to operate the circuit breaker to open the circuit, valve 156 is energized to admit fluid under pressure to the upper portion of the motor cylinder, and since it is highly desirable that the circuit opening operation take place at as high a speed as possible in order to obtain efficient and fast arc extinction, it will be observed that this is accomplished by motor 134, because the compressed gas is admitted to the large diameter portion 142 of the cylinder, thus operating on the large diameter portion 150 of the piston to exert the maximum force which the motor is capable of on the contact lever 114 during a circuit interrupting operation. It will thus be observed that during a circuit opening operation the maximum force of the motor is utilized to obtain rapid opening of the breaker contacts and consequently the most efficient circuit interruption characteristics. However, during a circuit closing operation but a small force is exerted during the first part of the movement

of contact lever 114 towards fixed contact structure 112, and a much greater force is automatically exerted during the final part of this operation when relatively high mechanical resistance is encountered.

Fig. 3 of the drawings illustrates a modified form of motor capable of use for operating a circuit breaker during the circuit closing operation with a variable force in substantially the same manner as the fluid motors described and illustrated in Figs. 1 and 2 of the drawings. The particular motor 168 illustrated in Fig. 3 comprises a cylinder having a large diameter portion 170 and a smaller diameter portion 172. There is provided within the motor cylinder a piston structure having a corresponding large diameter portion 174, and a small diameter portion 176. A fluid inlet port 178 is provided solely at the lower end of small diameter portion 172 of the cylinder, and in this particular instance, a vent 180 is provided at the upper end of the large diameter portion 170 of the cylinder. The motor piston is provided with an integral piston rod 182 projecting through the upper end of the cylinder to be connected with a breaker operating rod 184.

The motor 168 is arranged so that upward movement thereof, as viewed in Fig. 3, will cause a circuit closing operation. It will be observed then, that when fluid is admitted to inlet port 178, it will act only on the small diameter portion 176 of the motor piston. Accordingly, the first portion of the closing movement of a breaker operated thereby will not be excessively fast. However, as soon as the motor piston has moved an amount sufficient to cause the small diameter portion 176 to enter the flared upper end of the small diameter portion 172 of the cylinder, fluid under pressure will then be admitted to the large diameter portion 170 of the cylinder, and will act on the large diameter portion 174 of the piston, and thereby automatically increase the force available during the final portion of the circuit closing operation of a breaker operated thereby.

From the foregoing, it will be apparent that this invention provides a novel circuit breaker construction, having actuating means coordinated with the breaker contacts in a manner such that a relatively small force is exerted by the actuating means during the first portion of a circuit closing operation, and this force is automatically increased during the final part of the circuit closing movement to overcome the relatively large resistance encountered during this portion of the operation. Moreover, this is accomplished in a relatively simple manner with no moving parts or additional controls than those now employed in fluid operated breakers. Moreover, where the breaker may be operated to both open and closed circuit positions by the entire operating mechanism, the arrangement of this invention provides a circuit closing operation as described above, and a circuit opening operation where the full force which the operating means is capable of is exerted on the moving contact to obtain rapid opening of the contacts and consequent efficient and rapid arc extinguishment.

Having described preferred embodiments of the invention in accordance with the patent statutes, it is desired that the invention be not limited to these particular structures, inasmuch as it will be apparent to persons skilled in the art that many modifications and changes may be made in these particular structures without

departing from the broad spirit and scope of this invention. Accordingly, it is desired that the invention be interpreted as broadly as possible, and that it be limited only as required by the prior art.

I claim as my invention:

1. A circuit breaker comprising, separable contact means at least one of which is movable into and out of engagement with the other, fluid motor means for at least actuating said movable contact means in a direction to engage the other of said contact means, actuating mechanism connecting said motor means and movable contact for transmitting movement of said motor means to said contact means to close the breaker, means comprising a part of said motor means independent of said mechanism, which is operable to automatically increase the force exerted by said motor means during the final part of a circuit closing operation in response to closing movement of said motor means an amount sufficient to actuate said movable contact means from its open circuit position spaced away from the other of said contact means to a position in proximity to but still spaced from said other contact means.

2. A circuit breaker comprising, separable contact means at least one of which is movable into and out of engagement with the other, fluid motor means for at least actuating said movable contact means in a direction to engage the other of said contact means, actuating mechanism connecting said motor means and movable contact for transmitting movement of said motor means to said contact means to close the breaker, said motor means comprising a cylinder and piston one of which is movable and operatively connected with said actuating mechanism, said piston and cylinder having corresponding stepped portions differing in cross section area, means for admitting fluid under pressure to the cylinder portion of small cross section area to initiate circuit closing movement of said movable contact, and means responsive to circuit closing operation of said motor means an amount sufficient to actuate said movable contact means from its open circuit position spaced away from the other of said contact means to a position in proximity to but still spaced from said other contact means for automatically admitting said fluid under pressure to the cylinder portion of larger cross section to thereby increase the closing force transmitted to said contact means during the latter part of contact closing movement, and the last mentioned means including a fluid inlet for said large cylinder portion which is separate and independent of the fluid inlet for the small cylinder portion.

3. In a circuit breaker, separable contact means at least one of which is movable into and out of engagement with the other, fluid motor means for at least actuating said movable contact means in a direction to engage the other of said contact means, actuating mechanism connecting said motor means and movable contact for transmitting movement of said motor means to said contact means to close the breaker, said motor means comprising a cylinder and piston one of which is movable and operatively connected with said actuating mechanism, said piston and cylinder having corresponding portions differing in cross section area, means for admitting a fluid under pressure to said cylinder communicating with a port for each of said cylinder portions, the port for said cylinder portion of large cross section being covered by said piston when said movable breaker contact means is at its full open circuit

position, and is uncovered only in response to relative movement of said piston and cylinder an amount sufficient to actuate said movable contact means from its full open position to a position in proximity to the other of said contacts to thereby increase the closing force transmitted to said contact means during the latter part of contact closing movement.

4. In a circuit breaker, separable contact means at least one of which is movable into and out of engagement with the other, fluid motor means for at least actuating said movable contact means in a direction to engage the other of said contact means, actuating mechanism connecting said motor means and movable contact for transmitting movement of said motor means to said contact means to close the breaker, said motor means comprising a cylinder and piston one of which is movable and operatively connected with said actuating mechanism, said piston and cylinder having corresponding portions differing in cross section area, means for admitting fluid under pressure to the cylinder portion of small cross section area to initiate circuit closing movement of said movable contact, and said piston and cylinder portions of small cross section both being shorter than the travel of said piston so that said small piston portion is movable during a circuit closing operation out of said cylinder portion of small cross section to admit said fluid directly to the cylinder portion of large cross section by relative movement of said piston and cylinder from the full open position of said breaker an amount sufficient to actuate said movable contact means to a position in proximity with the other of said contact means to thereby increase the closing force transmitted to said contact means during the latter part of contact closing movement.

5. In a circuit breaker, separable contact means at least one of which is movable into and out of engagement with the other, fluid motor means for actuating said movable contact means, actuating mechanism connecting said motor means and movable contact for transmitting movement of said motor means to said contact means to close the breaker, said motor means comprising a cylinder and piston one of which is movable and operatively connected with said actuating mechanism, said piston and cylinder having corresponding portions differing in cross section area, means for admitting fluid under pressure to the cylinder portion of small cross section area to initiate circuit closing movement of said movable contact, means responsive to circuit closing operation of said motor means an amount sufficient to actuate said movable contact means from its open circuit position spaced away from the other of said contact means to a position in proximity thereto for automatically admitting fluid under pressure to the cylinder portion of larger cross section to thereby increase the closing force transmitted to said contact means during the latter part of contact closing movement, and means for admitting fluid under pressure to said cylinder portion of large cross section to cause a high speed circuit opening operation.

6. In a circuit breaker, separable contact means at least one of which is movable into and out of engagement with the other, fluid motor means for actuating said movable contact means, actuating mechanism connecting said motor means and movable contact for transmitting movement of said motor means to said contact means to close the breaker, means comprising a part of said motor means independent of said mechanism,

which is operable to automatically increase the force exerted by said motor means during the final part of a circuit closing operation in response to closing movement of said motor means an amount sufficient to actuate said movable contact means from its open circuit position spaced away from the other of said contact means to a position in proximity thereto, and means for causing said motor means to exert said greater force to separate said contact means to effect a circuit opening operation at a relatively high rate of speed.

7. In a circuit breaker, separable contact means at least one of which is movable into and out of engagement with the other, fluid motor means for at least actuating said movable contact means in a direction to engage the other of said contact means, actuating mechanism connecting said motor means and movable contact for transmitting movement of said motor means to said contact means to close the breaker, said motor means comprising a cylinder and piston one of which is movable and operatively connected with said actuating mechanism, said piston and cylinder having corresponding portions differing in cross section area, means for admitting a fluid under pressure to said cylinder communicating with a port for each of said cylinder portions, the port for

said cylinder portion of large cross section being covered by said piston portion of large cross section area when said movable breaker contact means is at its full open circuit position, and is 5 uncovered only in response to relative movement of said piston and cylinder an amount sufficient to actuate said movable contact means from its full open position to a position in proximity to the other of said contacts to thereby increase the 10 closing force transmitted to said contact means during the latter part of contact closing movement.
